CLAIM

The ornamental design for an integrated circuit chip carrier, as shown and described.

DESCRIPTION

FIG. 1 is a perspective view of an integrated circuit chip carrier showing my new design;

FIG. 2 is a top plan view thereof;

FIG. 3 is a bottom plan view thereof;

FIG. 4 is an end elevational view thereof; and

FIG. 5 is a side elevational view thereof, the opposite side elevational view being a mirror image.

FIG. 1

FIG. 2

FIG. 5

FIG. 4

FIG. 3
